A rectangular frame with a cross-hatched center and the number 28 in the bottom left corner. To the right is the word "INVENTOR." and below it is a signature.

UNITED STATES PATENT OFFICE

VINCENT G. APPLE, OF DAYTON, OHIO

GEARED MOTOR

Application filed March 1, 1930. Serial No. 432,543.

This invention relates to electric motor construction which combines with the motor elements suitable speed reducing gearing so arranged as to connect the high speed armature shaft to a power shaft to operate the power shaft at a relatively low speed.

An object of the invention is to so locate, enclose and segregate the gear mechanism and the necessary shaft bearings, all of which require more or less oil to keep them lubricated, as to obviate the danger of getting oil on the motor elements, particularly the commutator and brushes, to which oil is detrimental.

Another object is to combine in the one structure appropriate switch mechanism for starting and stopping the motor.

Another object is to simplify the insulating of the switch mechanism, the brushes and the winding terminals, each from the other, by making the head upon which these several elements are supported entirely of insulating material.

These and other objects are attained by the mechanism hereinafter described, reference being had to the drawings wherein—

Fig. 1 is a side elevation of the motor.

Fig. 2 is another side elevation looking at Fig. 1 in the direction of the arrow 2.

Fig. 3 is a top plan view of the motor.

Fig. 4 is a transverse section taken at 4—4 of Fig. 1.

Fig. 5 is a vertical axial section taken at 5—5 of Fig. 2.

Fig. 6 is a vertical axial section taken at 6—6 of Fig. 1.

Fig. 7 is a transverse section taken at 7—7 of Fig. 6.

Fig. 8 is a transverse section taken at 8—8 of Fig. 5.

Similar numerals refer to similar parts throughout the several views.

The housing 10, preferably die cast of metal, is divided into two main compartments, the upper or motor compartment 11 and the lower or gear compartment 12. The motor compartment 11 is cup shaped, open at the top, and has two bosses 13 projecting inwardly from opposite walls.

Bosses 13 are tapped at 14 and two studs 16

are screwed tightly into these tapped holes and extend upwardly therefrom. A laminated field core 17 is seated in the compartment 11 against shoulder 18 and is held thereagainst by clamps 19 and nuts 21. Coils 22 surround the poles 23 of the core and are held thereon by sheet metal clamps 24.

The lower or gear compartment contains all of the parts of the structure which require oil. The high speed armature shaft 25 rotates on the two ball bearings 26 and 27, the upper bearing 26 being seated directly in housing 10 while the other bearing 27 is seated in the knurled cap 28 which is screwed into the threaded opening 29. Opening 29 is of sufficient diameter to admit the upper bearing 26 at assembly. A threaded plug 30 may be removed to fill the gear compartment 12 with oil.

The low speed power shaft 31 is rotatably supported in a horizontal position by the two bearings 32 and 33, (see Fig. 8). Bearing 32 is held directly in the hub 34 of housing 10 while bearing 33 is supported in the cap 35 threaded at 36 in the housing. The cap 35 is sufficiently large to admit the worm wheel 37 at assembly. Worm threads 38 cut directly into the armature shaft 25 mesh with the teeth of worm wheel 37. An oil throw ring 39 above ball bearing 26 keeps oil from creeping up the shaft and getting into the motor compartment 11, the bottom of which is lower in the center than around the outer part thus tending to return any oil to the gear compartment 12 which may by chance have gotten into the motor compartment 11.

The armature core 40 and the commutator 41 are mounted on the sleeve 42 and coils 43 are wound on the core and about the sleeve as shown. The completed armature fits over the upper smaller portion of shaft 25 and is secured to the shaft by the nut 44 and the washer 46. Washer 46 has one integral key 47 extending radially inward into a short keyway 48 in shaft 25 and another integral key 49 bent over to extend axially into a notch 51 in the end of the sleeve 42 whereby driving rotation is established between the shaft 25 and the sleeve 42.

The head 52 carries the brush gear and the

motor switch and joins the housing 10 to form a closure about the moving parts, and, in order that the several electrical connections may be effectively insulated one from another, the entire head is made of molded insulation.

The head and the housing are rabbeted together at 53 and the studs 16 extend upwardly through the arcuate slots 54 whereby the head has limited rotative movement on the housing for brush adjustment. Nuts 56 secure the head to the housing when proper brush adjustment has been made. A hub portion 57 surrounds and encloses the commutator at some distance therefrom, and a smaller hub portion 58 fits the standard push button switch 59 more closely. Radially extending bosses 60 contain the brushes 61, the brush springs 62 and the brush spring caps 63. Metal inserts 64 convey current from the brushes to convenient terminal screws 66. Leads 67 emanating from the one end of each field coil are connected to these screws, the other ends of the coils being connected by leads 68 to screws 69 of switch 59, the hub 57 having outwardly bulging portions 71 through which the leads may pass.

A swivel eye 72 has a stem 73 adapted to turn freely in the small hub 74 of head 52, a spun over end 76 preventing the stem from being removed from the hub. An opening 77 is provided so that the motor may be hung on any suitable hook suspended from a convenient support.

The threaded hub 78 of cap 35 is adapted to receive the casing of a flexible shaft, and the end of the power shaft 31 is flattened as at 79 to provide a driving tang for rotating the flexible shaft. A lug 81 extending laterally from the gear compartment 12 has a squared opening 82. A forked hook 83 has a squared shank 84 which extends through this opening. A screw 86 holds the forked hook secured in position. Hook 83 is provided so that tools such as drills, grinding wheels, hair cutters and similar devices such as are customarily driven through flexible shafts may be hung up when not in use.

Having described my invention, I claim—

50. In a dynamo-electric machine, an end enclosing head of molded insulation having a central hub, an electric switch in said hub, a smaller hub at the end of the first hub, and a swivel in said smaller hub.

55. In testimony whereof I affix my signature.

VINCENT G. APPLE.
